UNITED STATES PATENT OFFICE.

AUGUSTE HENCHOZ AND FRITZ HENCHOZ, OF LOCLE, SWITZERLAND.

STOP-WATCH.

SPECIFICATION forming part of Letters Patent No. 392,729, dated November 13, 1883.

Application filed March 16, 1883. Serial No. 267,427. (Model.) Patented in England June 20, 1887, No. 8,843; in Italy August 18, 1887; No. 21,947/296, and in France November 2, 1887, No. 184,277.

To all whom it may concern:

Be it known that we, AUGUSTE HENCHOZ and FRITZ HENCHOZ, both residing at Locle, in Switzerland, have invented a new and useful 5 Improvement in Stop-Watches, of which the following is a specification.

This invention consists in a stop mechanism of a very cheap construction, in which the hand of the stop mechanism is directly acted 10 upon by a wheel fixed to the axis of the seconds-wheel of the train without any intermediate transmission.

The accompanying drawings show a stop mechanism constructed according to this in- 15 vention.

Figure 1 is a top view of the general arrangement of the stop mechanism; and Fig. 2 shows, on an exaggerated scale, the section of the pinion of the first wheel (center wheel) of the 20 works, with the axis of the stop-hand traversing the same.

The push-piece which acts upon the cam-ratchet G and the corresponding spring are not shown in the drawings, being of the usual 25 construction. Upon the axis A of the seconds-wheel there is fixed a fine toothed wheel, B, which turns continuously with the axis A. The arbor of the pinion C and center or first wheel is hollow, and within it is the axis D, 30 the pivot d of which passes through a little tube or plug, e, inserted into the tubular arbor C, and this axis D carries the hand E of the stop mechanism. The axis D also carries a fine-toothed pinion, H, and an eccentric or 35 heart-cam, I, the latter being acted upon by a lever, J, when the hand E is to be returned to its normal position of rest. This lever J is 40 acted upon, as usual, by the cam-ratchet G. The other end of the axis D to the hand is pro- 45 vided with a pivot, d', turning in the oscillating bridge F. This latter oscillates about a screw, f, and has a projection, F', which bears alternately upon a cam or in a notch of the cam-ratchet G. According to the position as- 50 sumed by the bridge F the pinion H is brought into or thrown out of gear with the wheel B—that is to say, that the stop-hand E is put into action or stopped by slightly moving the oscillating bridge F.

50 A spring, M, presses the bridge F in the direction of the wheel B, and thereby causes the

pinion H to be put into gear with the wheel B as soon as the projection F' falls into one of the notches of the cam G.

A friction - spring, K, bears continually 55 against the axis D and acts like a brake when the pinion H is out of gear. Fig. 2 shows the axis D in position for the hand to be rotated.

We are aware that in stop-watches the axis D of the stop-hand has passed through the 60 tubular arbor of the center or first wheel and has been fitted so as to oscillate within said arbor, and we are aware that rotation has been given to the arbor of the stop-hand by a wheel upon the arbor of the third wheel act- 65 ing through an intermediate wheel or pinion. In our improvement the intermediate gear-wheel is dispensed with, and the axis D is supported by and moves with the bridge F, and said bridge becomes a lever that swings 70 upon the pivot f, and it is not necessary to slot or elongate the hole for the pivot of the axis D, as has heretofore been usual when the axis was moved laterally to connect or disconnect the gear-wheels driving the independent 75 seconds-hand.

We claim as our invention—

1. The combination, with the center pinion, C, having a tubular arbor, of the wheel B upon the arbor of the seconds-wheel of the watch- 80 movement, the axis D, passing through the tubular arbor, the hand E, pinion H, and heart-cam I upon the axis D, and the lever-bridge F, pivoted at f and having a hole for the pivot of the axis D, and the cam ratchet- 85 wheel G, for giving motion to the lever-bridge and moving the axis and pinion laterally for stopping and starting the seconds-hand, substantially as specified.

2. In a stop-watch, the combination, with 90 the wheel B and cam ratchet-wheel G, of the lever-bridge F, the axis D, having its pivot in a hole in the lever-bridge, the heart-cam I, pinion H, and hand E upon the axis D, and a spring acting to press the bridge and pinion 95 H toward the wheel B, substantially as set forth.

AUGUSTE HENCHOZ.
FRITZ HENCHOZ.
